X-RAY TUBE

Malvern J. Gross and Zed J. Atlee, Chicago, Ill.,
assignors to General Electric X-Ray Corporation,
a corporation of New York

Application March 16, 1934, Serial No. 715,902

12 Claims. (Cl. 250—34)

The present invention has to do with an X-ray tube casing that affords both X-ray and electrical protection to the operator and patient, and relates particularly to structural features reducing the size of such casing and affording means of cooling the anode and the glass walls of the tube through the use of a single body of oil.

In such a tube, there is continual circulation of oil, hence there is no possibility of the destructive heating thereof. A tube of large capacity may thus be used in a relatively small casing with no sacrifice in electrical insulation. Such an arrangement as is herein illustrated and described provides maximum protection against tube breakdown, the means for preventing tube puncture being a distinct advance in the art. No previously designed tube has ever possessed facilities of equal merit for connecting high tension conduits to the tube. There are numerous refinements in tube structure which are later fully described.

Included in the objects of the invention are the following:

An X-ray tube casing of relatively small physical dimensions but which affords complete X-ray and electrical protection irrespective of atmospheric conditions, the casing being of relatively slight weight to permit easy handling.

A device of such character in which an insulating fluid surrounds and insulates the voltage carrying parts of the tube from an enclosing casing and affords a means for cooling the anode and glass walls of the tube, the structure being such that a cooling medium may be carried to and from the container in flexible tubing covered with grounded metal sheaths.

A novel means of supporting an X-ray tube in a desired position within a casing of the type described.

A unique structure for attaching cables to the device and for making electrical conductive connections between the cables and the terminals of an X-ray tube.

An improved arrangement whereby current carrying cables and cooling conduit terminals are placed so as not to interfere with one manipulating the tube and container therefor.

These objects and such other objects as may hereinafter appear are obtained by the novel construction, unique arrangement and improved combination of elements illustrated in the accompanying drawings, hereby made a part of this application, and in which:

Figure 1 is a longitudinal section of a device embodying the subject matter of the invention,

certain parts being in elevation for clarity of illustration;

Figure 2 is a section taken along the line 2—2 of Figure 1;

Figure 3 is a transverse section taken along 5 the line 3—3 of Figure 1 looking in the direction of the arrows.

Figure 4 is a fragmentary sectional view of the cathode end of the tube casing;

Figure 5 is a section taken along the line 5—5 10 of Figure 1;

Figure 6 is a view taken along the line 6—6 of Figure 4 and looking in the direction of the arrows;

Figure 7 is a fragmentary sectional view of 15 the tube and casing at the anode end; and

Figure 8 is a fragmentary sectional view of the device taken at the line 8—8 of Figure 7.

Like reference characters are used to designate similar parts in the drawings and in the 20 description of the invention which follows:

Reference should be had first to Figures 1, 2 and 3 wherein there is shown an X-ray tube 10 with an anode 11 and a cathode 12 suitably supported in a glass envelope 13. Said tube 25 has arms 14 and 15 which terminate respectively in a cathode base 16 and an anode base 11.

Surrounding the tube 10 is a metallic casing consisting of a center part 18, preferably of cast metal, and metallic hood members 19 and 20 attached to the center or sleeve part 18 in any desired fashion, as by means of the bolts 21. An aperture 18a, Figure 1, is provided in the lower central part of the central cylindrical part 18. Gaskets 22 may be interposed between opposing surfaces of parts 18, 19 and 20 to form oil-tight joints between such parts.

Snugly about the center section 23 of the tube 10, which center section is cylindrical and of greater diameter than the arms 14 and 15, is 40 an insulating sleeve 24, which preferably comprises material such as wound paper impregnated with any suitable insulating material, such as a phenol condensation product. Surrounding the sleeve 24 and secured thereto by means of 45 an adhesive phenol condensation product or other suitable material is an X-ray protective sleeve 25 of lead and of any desired thickness. When designed for use with an X-ray tube operating at approximately two hundred kilovolts, the wall 50 thickness of the sleeve 25 is about three-sixteenths inch. Such lead cylinder 25 is for the purpose of absorbing direct radiation from the X-ray tube.

An aperture 26 is provided in the cylinder or 55

sleeve 25 for the passage of a cone of useful X-rays. Surrounding the cylinder 25 and suitably secured thereto by means of a phenol condensation product varnish or the like is the outer part 5 18 heretofore mentioned. In practice, the center part 18 is produced as a separate unit. The insulating cylinder 24, the lead cylinder 25, and the center part 18 are concentrically arranged with respect to each other so that the apertures 10 18a and 26 aline to form a window 27 for the passage of the heretofore mentioned useful cone of X-light. Such parts are then firmly secured to each other by means of a suitable adhesive insulating compound. It is necessary to make 15 the joint between the opposing faces of the members 18, 24 and 25 oil tight to prevent leakage of oil between the members and out of the window 27. Mechanical rigidity between the concentrically joined members 18, 24 and 25 is insured 20 by the use of a plurality of screws 28 and washers 29, one of each being shown in Figure 1. A plurality of screws 28 and washers 29 are spaced complementarily about the periphery at each end of 25 the lead cylinder 25. The screws 28 thread into lugs 30 extending inwardly of cylindrical part 18 to draw the washers 29 against opposite ends of the lead cylinder.

The hoods 19 and 20 carry insulating tubes 31 and 32, respectively, held thereto by means of 30 a suitable cement. By overlapping the outer edges of the insulating cylinder 24, the tubes 31 and 32 prevent fortuitous discharge of electrical energy from the X-ray tube to the metallic walls of the tube casing, which includes the center 35 section 18 and the hoods 19 and 20.

When the X-ray tube 10 is inserted into the tube casing, it is arranged therewith so that the focal spot 35 on the anode head 36 is alined axially of the casing window 27. The base 16 of 40 the cathode is immovably attached to the side arm 14 of the tube 10 so that the distance from the focal spot 35 to the outer face of the cathode shield 36a is definitely fixed. Thus the focal spot 35 is fixed with respect to the base 16 where- 45 fore the tube will become properly oriented within the casing by simply adjusting the base 16 with respect to a certain indicium (not shown) upon the casing.

Attention is now directed particularly to Figure 4 wherein the manner of supporting the cathode end of the tube is illustrated. Each of the conductors 37 leading from the cathode of the tube 10 is passed through a bushing 38, which 50 extends through apertures provided therefor in the end of the base member 16. The inner side of the base member is lined with a layer 39 of lead. Escape of vagrant X-rays axially of the tube is prevented by the said layer of lead. Nuts 40 may be turned onto the inner ends of the bushings 38 to hold such bushings and the members 39 of lead to the base member 16. In support of the bushings 38 and hence of the cathode 55 end of the tube is an insulating block 41, the latter being preferably of "Bakelite". Recesses 42 within the member 41 contain metal terminal pieces 43 and 43a, which pieces are identical and into which may be slipped a metal lug 44 as the bushings 38 are inserted thereinto. Each of the 60 lugs 44 remains against the end of its respective bushing 38 where it is held by means of a soldered connection 45 to a conductor 37. The lugs 44 are slidably contained within the terminal pieces 43 and 43a so that electrical contact is had 65 therebetween even though the tube 10 is moved 70 75

slightly toward or away from the insulating member 41.

The insulating block 41 is engaged to a metal shield 46 by means of a screw 47. Supporting the shield member 46 is a bracket 48 made of insulating material and held thereto by screw 49. The insulating sleeve 31 to which the bracket 48 is attached by means of members 33 and 34 has already been described. Members 33 and 34 are preferably of a dielectric material. Inasmuch as 10 the cylindrical insulating member 31 engages the circular neck of the hood 19, the position of the insulating block 41 is predetermined transversely of the casing.

Angularly disposed within the upper body of 15 the insulating block 41 is a ring-shaped section 50 having an opening 51 therethrough. The opening 51 is for carrying an end of the cathode conductor cable 52 in the manner later to be described. Lining the opening 51 is a sleeve 54, 20 which is threaded externally and internally at its lower end as indicated at 55 and 56. Sleeve 54 is an electrical conductor and is connected to the terminal post 43 by means of a flexible lead or strip 57. Nuts 59 hold the conductor 57 in 25 engagement with the terminal post 43. One end of the lead 57 is held in firm electrical contact with the sleeve 54 by means of nuts 58 screwed upon the threads 55. Complemental nuts 59a and 60 connect opposite ends of a flexible lead 61, 30 respectively, to the terminal post 43a and a terminal post 62.

Engaging the internal threads 56 of the sleeve 54 is an insulating plug 63 having a shouldered passageway 64 therein. A coiled compression 35 spring 65 within the passageway 64 presses between the shoulder of the passageway and the head 66 upon the terminal post 62 to urge such post upwardly axially of the opening 51. The cup-like metallic member 46 serves as a shield 40 about the conductors 57 and 61 and their respective terminals to prevent electrostatic discharges between those parts and the metal casing about the tube.

Figure 4 shows the conductor cable 52 in cross 45 section. One conductor 67 comprises the center of the cable 52. About the conductor 67 is an insulating layer 68, then a tubular conductor 69, and a comparatively thick outer layer 70 of insulating material.

The insulating cylinder 32 provides a support for and means for centering the anode end of the tube with respect to the tube casing. A bracket 100, which is made of insulating material, extends between the cylinder 32 and a metallic cup-like shield member 101, the latter serving in the device similarly to the shield member 46 at the cathode end of the tube. Screw 102 and a pin 103 made of insulating material provide means of attachment of the ends of the bracket 100 to the member 32 at its end. Joined to the base member 17, which is attached directly to the anode 11, is a U-shaped piece 104. Leg 105 of the U-shaped piece 104 contains a large central aperture for receiving the butt of the base member 17 so as to make a good mechanical support therefor and to be immovable thereon. Anchored in the opposite leg 106 of the piece 104 axially of the tube 10 is a pin 107 slidably contained in an aperture 108 within the shield member 101. A spring 109 exerts a pressure between the shield member 101 and leg 106 of the U-shaped member 104 to press the tube 10 toward the cathode end of the casing to impinge the electrodes 44 against the bottom of their recesses 75

in the terminal members 43. Inasmuch as the head of the anode is measurably spaced from the cathode end of the tube, the focal spot of the anode will always register with the window 21 axially of the casing when the tube is urged to the limit of the movement toward the cathode support. Registration of the tube radially of the tube casing is insured because of there being two bushings 38 at the cathode end of the tube for guidance into the recessed member 41. Any variation of the tube from standard length is taken care of by the spring 109.

In the upper part of the shield 101 is provided a bushing 110 of electrical conducting material. Bushing 110 is adapted to receive and make electrical contact with a conductor in the cable 71 leading to the anode of the tube in a manner later to be described.

The cable 71 for conducting electrical energy to the anode end of the tube may be similar in all respects to the cable 52 as illustrated in Figures 1 and 7. The corresponding parts of the two cables 52 and 71 are designated by the same reference characters. Inasmuch as only a single conductor is used in connection with the anode, a single conductor cable may be used. As the cable 71 is presently employed, the center conductor 67 thereof is allowed to stand idle.

Insulating layer 70 of the cables 52 and 71 is composed of material that is unaffected by being immersed in oil, the material being such as wound varnished cambric. About the cable layer 70 is a metallic sheath 72, which may be used for connecting the casing to ground. It will be noted that the two cables 52 and 71 are led into their respective hoods 19 and 20 in the same manner; hence, the same reference characters will be used to designate the corresponding parts of the device for securing the cables to the casing. A supporting sleeve 73 surrounds each cable at the point of entrance to the casing to avert short bends at those sections of the cables and possible injury thereto. The sleeves 73 may be of various structures, but the preferred embodiment consists of a spiral winding of heavy steel wire tempered to provide a strong resilient support for the cables. Each cable 52 and 71 is heavily reinforced with insulating material 74 at the section passing into the casing. The body of insulating material 74 may be wound into shape from a strip of varnished cambric, so that the mid-section will coincide with the entrance to the casing, and the end sections taper each way to approach the diameter of the cable. This arrangement of insulating material provides an insulation gradient so that greater insulation is had where the dielectric stress is the greatest. Mechanically, the bodies of insulating material 74 serve to seal the cables into immovable connection with the casing and to prevent leakage of oil from the casing about the joint.

Castings 75 may be made of electrical conductor material such as metal. Their inner surfaces are tapered to conform to the taper of the insulation 74. At the inner side of each joint is a molded piece 76 of suitable insulating material. The inner surfaces of pieces 76 are tapered in the same fashion as that of the castings 75. As the parts 75 and 76 are drawn together by means of screws 77, such parts are adapted to displace and compress a portion 78 of the material 74, between their opposing surfaces to further insure an oil-tight joint. Anchorage of the parts 75 and 76 to their respective hoods 19 and 20 is had by means of screws 79 and gasket 80, which is inter-

posed between opposing surfaces of the casing and the casting 75, the latter sealing the openings to the hoods against the leakage of oil.

In the preparation of the cable 52 for electrical connection to the cathode of the tube 10, the cable is first skinned down at its inner end so that the conductors 67 and 69 are laid bare, as shown in Figure 4. Conductor 69 is cut shorter than conductor 67. A metallic cuff 81 is then soldered to conductor 69. Sleeve 81 is of a diameter 10 adapting it to fit snugly into the threaded sleeve 54, which lines the opening 51 within the insulating member 41. The end of the inner conductor 67 is left to project such a distance beyond the end of the cable as to abut against the head 15 66 of the movable terminal post 62 to displace the post a short distance in opposition to the urge of spring 65 and thereby cause an impinging electrical contact with the head of the post. Displacement of the end of the cable 52 from the 20 respective contacts 54 and 66 is precluded because of the binding connection between that section of the cable at the entrance to the casing and the casing. A perspective view of the flexible conductors 57 and 61 is shown in Figure 6. 25 Electrical energy may pass from conductor 67 to the terminal post 62, through flexible lead 61, through the binding post 43a, through the corresponding electrode 44 and its filament lead 37 to the filament of the tube. After passing 30 through the filament of the tube the energy has a return path by way of the other filament lead 37, its respective electrode 44 and binding post 43, the lead 57, sleeve 54, the cuff 81, and the cable conductor 69. 35

The anode cable 71 is prepared at its end within the casing in somewhat the same fashion as has been described in connection with the cable 52. That is, an end portion of the outer layer of insulation 70 is cut away to lay bare a section of 40 the conductor 69 therein. A cuff 82 is then slid over the bared part of the conductor and soldered thereto. The cuff 82 is of such a diameter as to slide into the bushing sleeve 110 to make a good electrical connection therewith. Electrical 45 energy may flow to the anode by way of the conductor 69 of cable 71, cuff 82, bushing 110, the shield member 101, spring 109, U-shaped piece 104, screw 93, block 90 to cooling conduit 88, and thence to the anode. 50

Within the base 17 of the anode is a cup-like member 83 of lead to prevent the passage of vagrant X-rays axially of the tube. Additional means for preventing the passage of X-rays axially of the tube is provided in the form of two 55 rings 84 and 85 of insulating material opaque to X-rays. Preferably the rings 84 and 85 are of a phenol condensation product impregnated with a metallic salt of high atomic weight. Rings 84 and 85 may be held in an abutting position to 60 the ends of the enlarged section 22 of the tube 19 by means of split collars 86 adapted to be clamped to the side arms of the tube by means of screws 87. Felt washers 85a are preferably interposed between rings 84 and 85 and the adjacent glass walls of the tube. 65

Extending axially into the butt of the hollow stem of the anode 11 are two tubes 88 and 89 for conducting a cooling medium to and from the heated end of the anode. These tubes are preferably made of a non-corrosive metal. The tube denominated 88 is for conducting the cooling medium, which may be oil, inwardly of the anode to discharge such medium against the inner wall thereof, whereas the tube 89 serves to conduct 70 75

such discharged medium outwardly thereof. A block 90, shown in Figures 7 and 8, having a passageway 91 therein is attached to an end of the inlet conduit 88 by means of a running nut 92. A set screw 93 provides an anchorage of the block 90 to the U-piece 104. Leading from the end of the passageway 91 opposite to which the tube 88 is connected is a tube 94 of insulating material. A conduit piece 95 is joined to conduit 94 by an elbow 96. A petcock member designated generally by the reference character 97 extends through an aperture 98 in the upper side of the cylindrical casting 18 where it is joined to a piece 99 having a passageway 115. The passage-way in the piece 99 is connected communicatively to the conduit 95 through the agency of a flexible conduit 116 and a coupling member 117. To prevent the piece 99 from becoming loosened from the casting 18, a set screw 118 may be employed.

Suitably attached to the upper end of the petcock 97 is a hose 119, which leads thereto from a pump (not shown) for forcing the cooling medium into the anode by way of the series of conduits and coupling members just described. The conduit 116 may be made of a ductile material such as block tin to provide flexibility therein permitting movement of the conduit system while making connection with the anode.

30 All parts of the conduit system including the hose 119 are of materials unaffected by the action of oil. A metallic braid 120 over the hose 119 may serve as a connection between the tube casing and ground.

35 An outlet for the oil pumped into the anode and into the casing by way of the hose 119 is provided by a petcock 121 and hose 122. The hose 122 may be covered by a grounded metallic braiding 123. When oil is pumped inwardly of the tube casing through the hose 119, the oil will flow successively through the petcock 97, piece 99, conduits 116, 95 and 94, channel 91 in block 90, through tube 88 into the anode, outwardly of the anode through tube 89 into the shield member 101, and out of the member 101 into the casing about the tube 10. When the casing becomes filled with oil, the petcock 121 and hose 122 provide an avenue of escape for more oil as it is forced into the casing. A pressure gauge 123a 40 may be installed to indicate the pressure of the oil within the casing. The oil, in addition to serving as a cooling medium for the anode, provides a dielectric between the tube and the casing. Lugs 39 projecting inwardly from the two ends of 45 the cylindrical casting 18 are spaced apart so that there is ample space between the upper side of the sleeve 25 and the casing 18 for the oil to circulate from one end of the casing to the other.

50 Depending from the casting 18 about the window 27 is an annular member 124 secured thereto by means of screws 125. From the annular member 124 depends a metal cone 126. Screws 127 provide a means of anchorage of the cone to the annular member 124. Lining the cone 126 is a metal sheet 128, preferably of lead so as to intercept X-rays departing from the cone of useful radiation. A screen 129 may be placed between the annular member 124 and the body of the cylindrical casing at the window 27 to cut down, limit or restrict the rays passing therethrough and outwardly of the cone member 126.

55 Because of the various parts of lead embodied in the tube casing and the parts 39 and 83, which are of lead, at the ends of the side arms of the

tube, none but the useful bundle of X-rays can escape from the casing. Moreover, the tube 10 is protected against electrical discharges that might otherwise cause a puncture in the glass envelope thereof. Such electrical protection of the 5 tube is had because of its being completely surrounded by a metallic sheath insulated therefrom and carried at ground potential. By filling the casing with an insulating oil, the clearances necessary between the current carrying parts and 10 the walls of the casing are materially reduced, thus providing that the casing need be of but relatively small volume and weight.

An X-ray tube encased in the manner herein illustrated and described is capable of withstanding extremely high loading for the anode is cooled by a continuous stream of cool oil forced through it under pressure. Inasmuch as the oil flows through the casing, the latter is continuously flushed and the oil therein is constantly moving 20 so that no foreign matter can collect to form an electrical conductive path between the glass envelope of the tube and the casing.

The manner in which a tube is alined with certainty within the casing has already been described. This makes replacement of a tube, in the event of its being impaired, a comparatively simple operation that may be performed by the person operating the tube. All connections of conductors to the tube are readily detachable to 30 lighten the task of removing a tube from the casing. Cables 52 and 71 are covered with insulating material that is unaffected by oil so that such cables may be immersed in the oil within the casing when connected electrically to the electrodes of the tube and thus obviate the necessity of providing an oil-proof connection extending into the oil and making the joint between the connection and the cable in air which would increase its dimensions materially. Whether the 35 cables are immersed or whether they are simply surrounded by an air space within the casing, a length of the insulation thereon must lie between that section of the cable passing through the wall of the metal casing and the end thereof where 40 the conductors are bared for connection with an electrode of the tube. This intermediate section of insulation prevents creepage of electrical energy between the bared end sections of the conductors and the casing. If the insulation is such 45 that it may be submerged in the oil, the length of insulation between the bared conductors and the wall of the casing may be disposed beneath the oil so that such wall may be carried inwardly to the surface of the oil thereby reducing 50 the size of the casing.

55 What is claimed as new and is desired to be secured by Letters Patent of the United States is:

1. An X-ray tube, a casing having walls of metal provided with a ground connection and enclosing said tube, oil insulation in said casing, cylindrical members within the body of such oil and of insulating material with overlapping ends disposed axially of the tube, and an insulating support at each end of said tube and engaging the 60 adjacent cylindrical member.

2. An X-ray tube, a casing for containing said X-ray tube and having a ground connection, oil insulation in said casing, there being a central casing member and end casing members at either 65 end of said central member in intercommunicative relation, means for detachably connecting said casing members one to another, and sleeves of insulating material arranged about and extending axially of such tube a distance substan- 70 75

tially coextensive with the overall length of said tube, each sleeve having an end section overlapping the end section of the next adjacent sleeve.

3. X-ray apparatus comprising an X-ray tube having a cathode and an anode provided with a face, a base upon the cathode end of said tube at a predetermined distance longitudinally of said tube from the face of said anode, cathode terminals projecting side by side from such end of the tube and beyond said base, a casing for said tube and having a window therein for the passage of X-rays from the face of said anode, there being oil insulation in said casing between said casing and said tube, and said casing having a ground connection, an insulating member in said casing at a distance from such window corresponding longitudinally to the distance between said base and the face of the anode of said tube, connecting sockets in said insulating member and cooperating with said cathode terminals for supporting the capped end of said tube and providing connections to said terminals, said insulating member providing an abutment for said cap to position the tube longitudinally of said casing, a single conductor cable and a multiple conductor cable extending into said casing, means in said insulating member for anchoring said multiple conductor cable, and electrical conductor members leading from the conductors in said multiple conductor cable to the connecting socket in said insulating member, said connecting sockets making connection with said terminals in a manner to permit of said tube being readily withdrawn from said insulating member and cooperating with said terminals to orientate said tube radially in said casing, and said conductor cables having insulation shaped for providing the proper potential gradient between the conductors in said cable and said grounded casing.

40 4. X-ray apparatus comprising an X-ray tube, a metal casing having a ground connection and enclosing said tube, said casing containing oil for insulating said tube therefrom, there being cable receiving apertures in said casing, high tension cable conductors having an insulating covering extending to adjacent their ends, the end of each cable being free from insulation and the covered section of each cable extending into said casing through one of the apertures therein, an electrical connection between the uncovered end of each conductor cable and said tube within the body of the oil in said casing, one section of the insulating covering upon the inwardly projecting portion of each cable conductor also being immersed in such oil, and an insulator in the shape of truncated cones joined base to base about each of said cables where it passes through such aperture to provide a proper potential gradient between the high tension conductor therein and the grounded tube casing.

5. X-ray apparatus comprising an X-ray tube having an anode and a cathode, a casing therefor, there being oil insulation between said casing and said tube and said casing having a ground connection, cathode terminals projecting from the cathode end of said tube, insulating members in said casing for supporting said tube at each end, a single conductor and a multiple conductor cable extending into said casing to conduct electrical energy to said X-ray tube, means attached to said insulating support members for anchoring said multiple cables in position relative to said X-ray tube, conductor members between said cathode terminals and the conductors in said multiple conductor cable, said conductor mem-

bers having contacts engaging said cathode terminals to permit of said tube being withdrawn from said support member and positioning said tube radially while in said casing, said anchoring means at the anode end of said tube connecting said anode to the conductor in said single conductor cable, and each of said cables having insulation shaped thereabout within said casing in the form of truncated cones joined base to base to provide a proper potential gradient between the conductors in said cables and said grounded casing.

6. The combination, with an X-ray tube, of means for protecting the tube against fortuitous discharge of electrical energy, comprising a container having metallic walls adapted to enclose a body of insulating oil and provided with a ground connection, a cover for said tube within said container comprising a solid dielectric material immersed in the insulating oil within said container, and means within said cover for supporting said tube, said X-ray tube comprising an anode and a cathode with anode and cathode connections respectively at the opposite ends thereof, said container being formed with demountable end portions each containing support means for the support of a bushing, a bushing on each of said support means, said bushing comprising a cable embodying a central conductor and a cylindrical sleeve-like conductor about the central conductor and insulation between and surrounding said conductors, the bushing support embodying a pair of cooperating conical sleeves through which the cable extends, said cable having a wrapping thereon within said conical sleeves and adapted to be compressed by and between the sleeves when the same are assembled in place whereby to provide a fluid-tight seal at the point of entrance of the cable into the container, and means to connect the cylindrical conductor of one cable with the anode connection of said tube and to connect both conductors of the other cable respectively with the cathode connections.

7. The combination, with an X-ray tube, of means for protecting the tube against fortuitous discharge of electrical energy, comprising a container having metallic walls adapted to enclose a body of insulating oil and provided with a ground connection, a cover for said tube within said container comprising a solid dielectric material immersed in the insulating oil within said container, and means within said cover for supporting said tube, the container comprising sections including a central tubular section and removable end sections, the X-ray tube being readily removable from the container upon the removal of an end section, said cover embodying portions mounted respectively on and within said end sections and carrying the insulating means for supporting the opposed ends of the tube.

8. The combination, with an X-ray tube, of means for protecting the tube against fortuitous discharge of electrical energy, comprising a container having metallic walls adapted to enclose a body of insulating oil and provided with a ground connection, a cover for said tube within said container comprising a solid dielectric material immersed in the insulating oil within said container, and means within said cover for supporting said tube, said container comprising a central tubular portion and removable end portions and said cover comprising an insulating sleeve carried by and within the tubular central portion of the container, and sleeve-like elements carried by

and within the removable end portions of the container and having ends projecting within the central tubular portion of the container in position to encircle the opposite ends of the insulating sleeve carried thereby.

9. The combination, with an X-ray tube, of means for protecting the tube against fortuitous discharge of electrical energy, comprising a container having metallic walls adapted to enclose a body of insulating oil and provided with a ground connection, a cover for said tube within said container comprising a solid dielectric material immersed in the insulating oil within said container, and means within said cover for supporting said tube, said container comprising a central tubular portion and removable end portions and said cover comprising an insulating sleeve carried by and within the tubular central portion of the container, sleeve-like elements carried by and within the removable end portions of the container and having ends projecting within the central tubular portion of the container in position to encircle the opposite ends of the insulating sleeve carried thereby, said insulating means for supporting the tube comprising clamping collars within said insulating sleeve for securing the central portions of the tube in place therein, and brackets on said sleeve-like elements for receiving the opposed ends of the X-ray tube.

10. The combination, with an X-ray tube, of means for protecting the tube against fortuitous discharge of electrical energy, comprising a container having metallic walls adapted to enclose a body of insulating oil and provided with a ground connection, a cover for said tube within said container comprising a solid dielectric material immersed in the insulating oil within said container, and means within said cover for supporting said tube, said container comprising a central tubular portion and removable end portions and said cover comprising an insulating sleeve carried by and within the tubular central portion of the container, sleeve-like elements carried by and within the removable end portions of the container and having ends projecting within the central tubular portion of the container in position to encircle the opposite ends of the insulating sleeve carried thereby, said insulating means for supporting the tube comprising clamping collars within said insulating sleeve for securing the central portions of the tube in place therein, brackets on said sleeve-like elements for receiving the opposed ends of the X-ray tube, the central portion of said container providing a window and said tube embodying an anode, one of said brackets being positioned at a predetermined distance from said window to register the anode with said window 60 when the tube is mounted in said bracket, and

yielding means on the other bracket for normally urging the tube longitudinally in order to maintain the anode in registration with the window.

11. The combination, with an X-ray tube, of means for protecting the tube against fortuitous discharge of electrical energy, comprising a container having metallic walls adapted to enclose a body of insulating oil and provided with a ground connection, a cover for said tube within said container comprising a solid dielectric material immersed in the insulating oil within said container, and means within said cover for supporting said tube, the container comprising a central tubular portion and removable end portions of identical construction, bushings of substantially identical construction on said end portions and embodying each a cable comprising a central conductor and a sleeve-like conductor about the central conductor and insulated therefrom, and an end support bracket for said tube in each of said end portions of the container and supported by the insulating means, the conductors of one cable being connected with terminals of one of said brackets and the sleeve-like conductor of the other cable being electrically connected with a terminal on the other bracket whereby the tube may be assembled in or dismounted from the container by merely removing one of the end portions thereof.

12. The combination, with an X-ray tube, of means for protecting the tube against fortuitous discharge of electrical energy, comprising a container having metallic walls adapted to enclose a body of insulating oil and provided with a ground connection, a cover for said tube within said container comprising a solid dielectric material immersed in the insulating oil within said container, and means within said cover for supporting said tube, the container comprising a central tubular portion and removable end portions of identical construction, bushings of substantially identical construction on said end portions and embodying each a cable comprising a central conductor and a sleeve-like conductor about the central conductor and insulated therefrom, an end support bracket for said tube in each of said end portions of the container and supported by the insulating means, the conductors of one cable being connected with terminals of one of said brackets and the sleeve-like conductor of the other cable being electrically connected with a terminal on the other bracket whereby the tube may be assembled in or dismounted from the container by merely removing one of the end portions thereof, and means supported on the central tubular portion of the container for circulating insulating oil into and out of the container.
